U.S. Appl. No. 29/576,377, filed Sep. 2, 2016; George Alan Robusti.

* cited by examiner

Primary Examiner — Elizabeth J Oswecki(74) *Attorney, Agent, or Firm* — Sterne, Kessler,
Goldstein & Fox P.L.L.C.(57) **CLAIM**

The ornamental design for a shoe, as shown and described.

DESCRIPTION

FIG. 1 is a top, front perspective view of a shoe showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in the figures show portions of the shoe that form no part of the claimed design.
